DESIGN FOR A SAUCEPAN

Daniel T. Bergman, San Francisco, Calif.

Application March 12, 1945, Serial No. 118,427

Term of patent 14 years

(Cl. D44—1)

To all whom it may concern:

Be it known that I, Daniel T. Bergman, a citizen of the United States of America, resident of San Francisco, in the county of San Francisco and State of California, have invented a new, original, and ornamental Design for a Saucepan, of which the following is a specification, reference being had to the accompanying drawing, forming a part thereof.

Fig. 1 is a top plan view of a saucepan showing my new design; and

Fig. 2 is a side elevation of the same.

The essential features of my design reside in the parts shown in full lines.

I claim:

The ornamental design for a saucepan, substantially as shown and described.

DANIEL T. BERGMAN.
